(57) CLAIM

I claim the ornamental design for a sandal strap with martial arts designator, as shown and described.

DESCRIPTION

FIG. 1 is a perspective view of a sandal strap with martial arts designator, showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines showing a sandal sole in the figures are included for the purpose of illustrating the invention in use, and form no part of the claimed design.
